CONTINUOUS STRIP ANNEALING FURNACE

Herbert C. Greer, Morgantown, W. Va., and Herman C. Cappel and Robert W. Shoemaker, New Philadelphia, Stone Nyberg, Dover, Adolph Friedman, Cleveland, and Milton M. Rose, East Cleveland, Ohio

Application July 27, 1933, Serial No. 682,430

6 Claims. (Cl. 266—3)

The invention relates to a furnace for the continuous annealing or heat treating of strips of ferrous or nonferrous metal.

An object of the improvement is to provide a furnace through which one or more strips of sheet metal may be continuously passed at a uniform rate of speed, the strips being first heated to the necessary temperature required for the annealing or heat treatment desired and then cooled to the temperature required for the annealing or heat treating desired and quenched in a single continuous operation.

Another object of the improvement is to provide a furnace of this character in which the strips are passed first through a heating chamber where they are brought up to the required temperature and then through a cooling chamber of relatively small cross sectional area in which they are cooled at the desired rate.

A still further object is to provide a furnace of this character including a heating chamber, a precooling chamber of relatively small cross sectional area and a final cooling chamber of larger cross sectional area than the precooling chamber but of considerably less cross sectional area than the heating chamber.

Another object is to provide a furnace of this character having a heating chamber provided with spaced pairs of rolls, each pair being connected to one side of an electric circuit, the circuit between the two pairs of rolls being completed through the strip for rapidly heating the strip to the desired temperature, a cooling chamber of relatively small cross sectional area being located beyond the heating chamber for rapidly cooling the strip.

A further object is to provide means for driving the second pair of rolls at a slightly greater speed than the first pair in order to compensate for any elongation of the strip due to heating of the same, a friction clutch being provided upon said second pair of rolls for preventing tearing or undue stretching of the heated strip.

Another object is to provide means for water cooling each set of rolls in order to prevent undue heating of the same.

A further object is to provide means for admitting hydrogen or a mixture of nitrogen and hydrogen, or other gas to the furnace for producing bright annealing; or for admitting steam for blue annealing; or for admitting a vapor from nitric acid and/or hydrogen and nitrogen, or a vapor of sulphuric acid and salt, for producing a silver gray finish or etched effect upon the strips.

Another object of the improvement is to provide means for circulating water or other cooling agent through the cooling chamber, but not in contact with the strip, for the purpose of rapidly cooling the strip.

A still further object is to provide means for adjusting the rolls so as to place more or less tension upon the strip passing between the rolls in order to vary the softness or hardness of the strip.

A still further object is to provide means for varying the tension at different points throughout the length of the rolls in order to anneal one edge of the strip softer than the other edge or to anneal the edges of the strip either softer or harder than the central portion thereof.

The above objects, together with others which will be apparent from an inspection of the drawings and the following description or which will be further pointed out, may be attained by constructing the improved furnace in the manner illustrated in the accompanying drawings, in which

Figures 1a, 1b and 1c show a side elevation of the improved furnace;

Figs. 2a, 2b and 2c show a top plan view of the same;

Fig. 3 is a transverse sectional view through the pre-cooling chamber taken on the line 3—3, Fig. 1b;

Fig. 4, a transverse section through the final cooling chamber taken on the line 4—4, Fig. 1b;

Fig. 5, an enlarged side elevation of the heating chamber portion of the furnace;

Fig. 6, an enlarged vertical longitudinal section view through the heating chamber taken on the line 6—6, Fig. 2a;

Fig. 7, an enlarged side elevation of the heating chamber portion of the furnace showing the opposite side from that illustrated in Fig. 5;

Fig. 8, an enlarged fragmentary sectional view through the first pair of rolls taken on the line 8—8, Fig. 5;

Fig. 9, a transverse section through the upper roll shaft of the first pair of rolls taken on the line 9—9, Fig. 8;

Fig. 10, an enlarged detail section showing the guide rolls for guiding the strip into the heating chamber taken on the line 10—10, Fig. 6; and

Fig. 11, an enlarged transverse sectional view through the heating chamber and the second pair of rolls taken on the line 11—11, Fig. 5.

Similar numerals refer to similar parts throughout the drawings.

A strip to be annealed or heat treated in the

improved furnace may be formed into a coil as shown at 12 in Figs. 1a and 2a and placed in a box 13 located near the charging end of the furnace, the free end of the strip being preferably passed upward over a pulley 14 and then down around a pulley 15 located within a tank or trough 16 adapted to contain oil or the like as indicated at 17.

The pulley 14 may be journaled in vertically adjustable bearings 18 slidably mounted in a depending supporting frame or bracket 19, cables 20 provided with counterweights 21 being connected to the bearings 18 and located over pulleys 22, upon the frame or bracket 19, for the purpose of normally taking the slack out of the strip between the box 13 and tank 16.

A pair of blocks 23, having opposed faces covered with any suitable sort of friction material, as indicated at 24, may be mounted upon the box 13, the strip being drawn between said blocks as shown in Fig. 1a, means being provided for placing a tension upon the strip as indicated at 25. The coil 12 is thus prevented from being unwound more rapidly than is necessary for the operation of the furnace.

The vertical adjustment of the pulley 14 compensates for the time required for welding or otherwise attaching the ends of strips together so as not to interfere with the continuous movement of the strips through the furnace.

The furnace proper includes the heating chamber 26 which may be mounted upon a table or bench comprising the metal top plate 27 and the uprights 28. The table top 27 may form the bottom wall of the heating chamber, the side walls 29 and end walls 29' being preferably formed of metal plates. The top wall of the heating chamber may be in the form of a removable cover 30 having depending angular flanges 31 at its edges adapted to extend into the trough 32 surrounding the upper portions of the side and end walls and adapted to contain water, sand or the like for forming a gas-tight seal.

Two spaced pairs of rolls formed of brass, bronze or other suitable metal are located within the heating chamber 26, the upper and lower rolls of the first pair, located at the receiving or charging end of the chamber, being designated by the numerals 33 and 34 respectively, while the upper and lower rolls of the second pair, or that adjacent to the discharge end of the heating chamber, are designated by the numerals 35 and 36 respectively.

Each of these rolls is preferably hollow, as illustrated in the drawings, for the purpose of circulating water or other cooling medium therethrough. The necks or shafts 37 and 38 of the rolls 33 and 34 respectively are preferably hollow for the purpose of admitting water or other cooling agent to the rolls, and for the same purpose the necks or shafts 39 and 40 of the rolls 35 and 36 respectively are also preferably hollow.

In order to circulate water or other cooling agent through the hollow shafts and rolls, a hose 41 is connected to one end of each shaft for inlet and discharge of the water or other cooling agent while the opposite ends of each pair of shafts are connected together by a U-shaped hose 42, water-tight swivel connections 43 being provided between the hose and the hollow shafts, so as to allow rotation of the shafts without permitting leaking of the water or other cooling agent at the joints.

The end wall 29' of the heating chamber adjacent to the rolls 33 and 34 is provided with

a charging opening 44 at the level of the bench of the rolls 33 and 34. This charging opening is preferably provided with a neck 45 having the angular flange 46 surrounding the same to which the flange 47 of the charging tube 48 may be connected as by bolts 49, a gasket 50 being preferably provided between the flanges to produce a gas-tight joint.

The charging tube 48 extends downward at an angle from the heating chamber, the lower or inlet end thereof being located beneath the level of the oil in the tank 16 as best shown in Fig. 1a so as to form an air-tight seal at this point.

A pair of small rollers 51 is located within the lower portion of the charging tube 48 and preferably covered with suitable absorbent material for wiping the oil from the strip as it passes upward between the rolls. At the upper end of the tube 48 is located a pair of guide rollers 52 having substantially V-shaped peripheral grooves 53 to receive the edge portions of the strip and guide the same through the charging opening 40 to the rolls 33 and 34. The guide rollers 52 may be adjusted for strips of various widths by means of the adjusting screws 54 and nuts 55 as shown in Fig. 10.

A stack 56 may be located at the upper end of the tube 48 and provided with an outlet 57 controlled by a valve 58 by means of which the gases produced by the drying of the oil upon the strip, as it passes through the tube 48, may escape. In order to accelerate the drying of any oil which remains upon the strip after passing through the wiping rolls 51, a gas burner 59 may be located beneath the tube 48. This gas burner may also be used to preheat the strip before it enters the heating chamber.

For the purpose of driving the rolls 33, 34, 35 and 36, a motor 60 may be located beneath the table 27, the shaft 61 thereof having a small sprocket 62 fixed thereon. A sprocket chain 63 is located over this pinion and over a large sprocket 64 fixed upon the shaft 65 journaled in bearings 66 mounted upon a cross-frame 67 supported by the uprights 28 of the table.

A small sprocket 68 is fixed upon the shaft 65 and the sprocket chain 69 is located over said pinion and around the large sprocket 70 fixed upon the shaft 71 journaled in bearings 72 mounted upon the cross-frame 67.

A pair of small sprockets 73, preferably of the same size, is fixed upon the shaft 71 and a sprocket chain 74 is located around one of said sprockets 73 and around a large sprocket 75 fixed upon the shaft 38. A sprocket chain 76 is located around the other sprocket 73 and around a large sprocket 77 mounted upon the shaft 40, the sprocket 75 being slightly larger than the sprocket 77, whereby the rolls 35 and 36 will be driven at a slightly greater surface speed than the rolls 33 and 34 in order to compensate for elongation of the strip due to the rise in temperature therein and to keep the strip taut as it passes through the heating chamber.

Gears 78 and 79 are fixed upon the shafts 37 and 38 respectively and mesh with each other for the purpose of causing the rolls 33 and 34 to both be driven in unison and for the purpose of driving the rolls 35 and 36 in unison, gears 80 and 81 are fixed upon the shafts 39 and 40 respectively and mesh with each other.

The sprocket 75 may be fixed to the gear 79 as by the cap screws 82 but for the purpose of preventing tearing or undue stretching of the strip, the sprocket 77 may be frictionally mounted

upon the shaft 40. This may be accomplished by rotatably mounting the sprocket 77 upon the shaft and providing a disk 83 of fiber or the like upon each side of the sprocket, one of these disks 5 contacting with the adjacent side of the gear 81 and the other disk being engaged by the disk flange 84 of a sliding sleeve 85 upon the shaft, a spring 86 being located between said sliding sleeve and the collar 87 fixed upon the shaft, whereby 10 the sprocket 77 is frictionally mounted upon the shaft 40 so as to normally drive said shaft but arranged to slip upon the shaft to prevent tearing of the strip.

The shaft 38 is journaled in bearings 88 fixed in 15 the uprights 89, mounted upon the table 27, and having suitable bushings 90 therein. The shaft 37 is journaled in bearings 91 also provided with bushings 92 and slidable within vertical slots 93 in the uprights 89, a coil spring 94 being located 20 between the underside of each bearing 91 and a suitable socket 95 in the lower end of the slot 93 while a similar coil spring 96 is located between the upper end of each bearing 91 and a socket 97 in the upper end of the slot 93, an 25 adjusting screw 98, operated by a knob or wheel 99 engaging the upper end of each spring 96 to compress the same in order to vertically adjust each bearing 91. Thus the upper roll 33 may be 30 adjusted relative to the lower roll 36 to accommodate strips of various gauges.

It has also been learned by experience that by placing more tension upon one end of the roll 33 than upon the other end, one edge of the strip 35 may be annealed softer than the other edge. In the same manner, the edge portions of the strip 36 may be annealed either softer or harder than the central portion thereof by slightly convexing or concaving the surface of one of the rolls 33 or 34.

In order to provide an air-tight seal around 40 the shafts 37 and 38, at the points where they pass through the side walls of the heating chamber, and at the same time to permit the vertical adjustment of the upper shaft without breaking 45 the seal, a casting or the like as indicated at 100 is connected to each side wall 29 as by the bolts 101, a sheet of asbestos or the like as indicated at 102 being interposed therebetween.

Tubular portions 103 are provided upon the 50 casting to surround each of the shafts 37 and 38, these tubular portions being of larger inside diameter than the exteriors of the shafts, as are also the openings 104 in the side wall 29, through 55 which the shafts are located. Angular flanges 105 surround the outer ends of the tubular portions 103.

A collar 106 surrounds the lower shaft 38 and is provided with an angular flange 107 connected to the lower flange 105 as by bolts 108, a sheet 60 of asbestos or the like, as indicated at 109, being interposed between the flanges 105 and 107. A stuffing box or gland 110 is threaded upon the end of the collar 106 and asbestos or other suitable material as indicated at 111 is compressed 65 therein for the purpose of forming an air-tight seal around the shaft 38.

A similar collar 112 is located around the shaft 37 and provided with an angular flange 113 having elongated vertical slots 114 therein through 70 which are located the bolts 115 which connect the flange 113 to the upper flange 105, coil springs 116 being located around the bolts for normally pressing the flange 113 against the sheet of asbestos or the like located between the same and the 75 flange 105 as indicated at 117. These slots 114

permit of vertical adjustment of the corresponding end of the shaft 37 by means of the adjusting screw 98.

A stuffing box or gland 118 is threaded upon the end of the collar 112 and asbestos or the like 5 as indicated at 119 is compressed therein to form a gas-tight joint around the shaft 37.

The shaft 40 is journaled in bearings 120 formed of suitable insulation material and provided with bushings 121, the bearings 120 being mounted in uprights 122 supported upon the table 27. In the same manner the shaft 39 is journaled in insulation bearings 123 having bushings 124, these bearings being located in the vertical slots 125 formed in the uprights 122. 15

A coil spring 126 is interposed between the lower side of each bearing 123 and a socket 127 formed in the lower end of the slot 125, and a coil spring 128 is interposed between the upper side of each bearing 123 and the adjusting screw 129 20 which extends into the socket 130 and is provided with a knob or wheel 131 for adjusting the tension upon the springs.

A casting or the like including a flat plate 132 is attached to each side wall 29 of the heating 25 chamber as by means of bolts 133, a sheet of asbestos or the like, as shown at 134, being interposed between each plate 132 and the adjacent side wall. Each side wall 29 is provided with openings 135 of greater diameter than the shafts 30 39 and 40, through which openings the shafts are located, and each plate 132 is provided with tubular necks 136 arranged to register with said 35 openings and having annular flanges 137 at their outer ends.

The flange 138 of a collar 139, surrounding the upper shaft 39, is attached to the upper flange 137 so as to permit vertical movement of the collar 139 relative to the flange 137. A disk of asbestos or the like as shown at 140, and a 40 disk of fiber or other suitable insulation material, as shown at 141, are located between the flanges 137 and 138, insulation bushings 142 being located through suitable openings in the flanges 138 and the insulation disk 141, said bushings 45 being provided with vertical slots 143 through which are located bolts 144 which extend through the flange 137, coil springs 145 being interposed between each bushing and the head of each bolt in order to frictionally hold 50 the flanges 137 and 139 together with the disks 140 and 141 frictionally retained between said flanges.

A stuffing box or gland 146 is threaded upon the end of the collar 139 and compresses there- 55 in asbestos or other suitable material as shown at 147 to provide a gas-tight joint around the shaft 39. The lower shaft 40 is surrounded by a collar 148 having an annular flange 149 attached to the lower flange 137, disks 150 and 151 60 of fiber or other suitable insulation material and asbestos or the like respectively, being located between the flanges 137 and 149, bushings 152 of fiber or other suitable insulation material being located through suitable openings in the 65 flange 149 and disk 150 and bolts 153 being located through said bushings and through the asbestos disk 151 and flange 137 for connecting the parts together.

A stuffing box or gland 154 is threaded upon 70 the collar 148 and compresses asbestos or like material, as indicated at 155, in order to produce a gas-tight joint around the shaft 40.

It will thus be seen that the upper roll 35 may be adjusted relative to the lower roll 36 to ac- 75

commodate strips of various gauges and either end of the roll 35 may be adjusted relative to the other end thereof in order to produce greater tension upon one edge of the strip in order to anneal one edge of the strip softer than the other edge, in the same manner as described regarding the rolls 33 and 34, and one of the rolls 35 or 36 may have its surface slightly convexed or concaved if it is desired to anneal the edges or the central portion of the strip softer or harder as desired.

A valved outlet 156 may be provided in the top of the heating chamber, for use when hydrogen or other gas is being used in the furnace 15 in order to indicate when the heating chamber is properly filled with the gas which may be burned as it escapes from the outlet 156.

A plate 151 of brass or the like may be located between the rolls 34 and 36 and inclined 20 upward toward the latter to assist in guiding the strip between the rolls, said plate being supported by uprights 158 insulated from the table 27 as by the insulation blocks 159. Shoes 160 of brass or the like may be extended into the 25 outlet neck 161 of the heating chamber to guide the strip therefrom and are insulated from the heating chamber. A window 162 may be provided in each side wall of the heating chamber, adjacent to the rolls 35 and 36 so that the operator can see the strip as it passes between the rolls and can judge the temperature thereof from the color of the strip.

For the purpose of passing current through the strip between the rolls 33-34 and 35-36, 35 one roll of each pair is connected to an electric circuit. A cable or wire 163, leading from the positive side of the circuit, is connected to the bus bars 164 which are clamped, as shown at 165, to a shoe 166 contacting with the shaft 38 and 40 being held in frictional contact therewith as by the springs 168.

A similar shoe 169 is held in contact with the shaft 40 by the springs 170 and the bus bars 171 are clamped to said shoe as indicated at 172, 45 the cable 173, connected to the negative side of the circuit, being attached to said bus bars. Thus when a strip is passing through the heating chamber, the portion of the strip between the rolls 33-34 and 35-36 becomes a conductor, 50 completing the circuit between the rolls and the strip is heated up by the resistance of the current passing therethrough.

The cooling chamber is of considerably less cross sectional area than the heating chamber 55 and is preferably formed of two tubular sections comprising the precooling chamber 174 and the final cooling chamber 175, the precooling chamber being of considerably less cross sectional area than the final cooling chamber. Insulation 60 bushings are provided around the bolts to insulate the cooling chamber from the heating chamber.

The discharge neck 161 of the heating chamber 65 may be provided at its end with an angular flange 176 and the adjacent end of the precooling chamber may be provided with a similar flange 177, the flanges being connected together as by bolts 178, a sheet of asbestos or the like as indicated at 179 being preferably clamped between the flanges.

A plate of brass or the like as indicated at 180 is preferably provided upon the bottom of the precooling chamber so that the strip, which is indicated at S throughout the drawings, will 75 not be scratched as it is moved over the same.

For the purpose of heating the cooling chamber to the proper temperature, before the operation of the furnace is started, a gas burner 181 may be located beneath the same. As soon as the furnace starts to operate, the hot strip passing from the heating chamber will maintain the precooling chamber at sufficient temperature to permit the gas burner to be turned off.

For the purpose of producing blue annealed strips, steam may be admitted to the precooling 10 chamber, at a point adjacent to the heating chamber, as by the pipes 182, so that the steam will be impinged upon the strip just after it emerges from the heating chamber and while it is still at a relatively high temperature. 15

A sump 183 is provided in the bottom of the precooling chamber to collect the water of condensation, a valved outlet 184 being provided thereon, and the brass plate 180 being perforated above the sump as shown in Fig. 1b, so that the 20 water of condensation may drain through the same into the sump.

For the purpose of producing bright annealed strips, hydrogen or a mixture of hydrogen and nitrogen, or other suitable gas or combinations 25 of gas, may be admitted through the pipe 185.

The adjacent ends of the precooling chamber and final cooling chamber may be provided with flanges 186 adapted to be clamped together with a gasket 187 of asbestos or other suitable material located therebetween to provide a tight joint. Both the precooling and cooling chambers may be supported upon uprights 188. The final cooling chamber, as best shown in Fig. 4, may comprise the channel shaped trough 189 above which 35 is spaced a second channel shaped trough 190 having a brass plate 191 in the bottom thereof over which the strip is adapted to be moved.

The top wall of the chamber 175 may comprise a curved sheet or plate 192 tightly clamped 40 upon the bottom portion 189 as by the clamps 193. Water may be admitted to the lower channel 189 through a pipe 194 located near the inlet end of the chamber 175 and may be discharged therefrom through a pipe 195 swiveled 45 in the side of the lower channel 189 near the discharge end of the chamber, said pipe 195 having an angular extension 195a to which a drain hose 196 may be connected. By rotating the pipe 195 to raise or lower the angular extension 195a, the 50 level of water in the channel 189 may be controlled.

The discharge tube 197 extends downward at an angle from the end of the final cooling chamber, the adjacent ends of the discharge tube and 55 cooling chamber being provided with flanges 198 clamped together with a gasket 199 of asbestos or the like interposed therebetween to produce a gas-tight seal. The lower end of the discharge tube extends into the quenching tank 200, below 60 the level of the bath of oil or other quenching fluid therein and passes beneath the pulley 201 and then upward between the blocks 202, the opposing surfaces of which may be provided with any suitable absorbent material as shown at 203 65 to wipe the oil or the like from the strip, which is then coiled upon the reel 204 mounted upon a frame 205 located beyond the quenching tank and driven at a speed corresponding to the speed of the rolls 33-34 and 35-36. 70

For the purpose of driving the reel 204, a gear 206 may be fixed upon the shaft 207 of the reel and meshes with a pinion 208 upon the drive shaft 209 which may be driven by a motor or suitable source of power. 75

In the operation of the furnace, the gas burners 59 and 181 may be lighted and the current is turned on to the cables 163 and 173. The motor 60 is started and the reel 204 is driven at the proper surface speed to correspond to the travel of the strip through the rolls in the heating chamber.

The strip is passed from the coil 12 through the wipers 23 over the pulley 14 and under the pulley 15 in the oil tank 16, the surplus oil being wiped from the strip as it passes between the wiping rolls 51 in the tube 48. The strip is then guided through the rollers 52 to the heating chamber and as it passes between the rollers 33-34 and 35-36 it completes the circuit between the rolls 34 and 36, the strip being heated up by resistance.

The operator, by looking at the strip through the window 162 or 162a, can judge the temperature of the strip by the color of the same and can control the temperature by the amount of current supplied to and tension placed upon the rolls.

As the strip passes into the precooling chamber 174, it is cooled down quite rapidly and in actual practice may be cooled to about 100 degrees Fahrenheit before entering the final cooling chamber in which it is cooled down to substantially room temperature, after which it passes through the discharge tube 187 and quenching tank 200, the surplus oil being then wiped from the strip as it passes between the wiping blocks 202 prior to being coiled upon the reel 204.

The strip may be bright annealed by admitting hydrogen or other suitable gas or combinations of gases to the cooling chamber, or may be blue annealed by admitting steam to the cooling chamber. In order to assure sufficient gas pressure throughout the entire furnace, the valves upon the valved outlets 156 and 210, at opposite ends of the furnace, may be opened to allow a small amount of the gas to escape and this gas may be ignited so that the operator will know that sufficient gas is contained within the furnace as long as the flames continue to burn at these points.

We claim:

1. An annealing furnace including a gas-tight heating chamber, and a gas-tight cooling chamber of relatively great length and small cross sectional area as compared with the heating chamber, two spaced pairs of metal rolls journaled through the walls of the heating chamber, one roll of each pair being located in one side of an electric circuit whereby a strip of metal passed through the furnace will be heated by resistance as it passes between said rolls and will be allowed to cool as it passes through the cooling chamber, and means providing insulated gas-tight bearings for said rolls.

2. An annealing furnace including a heating chamber, and a cooling chamber of relatively great length and small cross sectional area as compared with the heating chamber, two spaced pairs of metal rolls journaled through the walls of the heating chamber, one roll of each pair being

located in one side of an electric circuit whereby a strip of metal passed through the furnace will be heated by resistance as it passes between said rolls and will be allowed to cool as it passes through the cooling chamber, means providing insulated gas-tight bearings for the rolls, and means for sealing said chambers gas-tight.

3. An annealing furnace including a heating chamber, and a cooling chamber of relatively great length and small cross sectional area as compared with the heating chamber, two spaced pairs of metal rolls in the heating chamber, one roll of each pair being located in one side of an electric circuit whereby a strip of metal passed through the furnace will be heated by resistance as it passes between said rolls and will be allowed to cool as it passes through the cooling chamber, means for sealing said chambers gas tight, and means for varying the tension upon said rolls without breaking said gas-tight seal. 20

4. An annealing furnace including a heating chamber, and a cooling chamber of relatively great length and small cross sectional area as compared with the heating chamber, two spaced pairs of metal rolls in the heating chamber, one roll of each pair being located in one side of an electric circuit whereby a strip of metal passed through the furnace will be heated by resistance as it passes between said rolls and will be allowed to cool as it passes through the cooling chamber, and means for varying the tension upon opposite ends of said rolls to anneal one edge of the strip softer than the other edge thereof. 25

5. An annealing furnace including a heating chamber, and a cooling chamber of relatively great length and small cross sectional area as compared with the heating chamber, two spaced pairs of metal rolls in the heating chamber, one roll of each pair being located in one side of an electric circuit whereby a strip of metal passed through the furnace will be heated by resistance as it passes between said rolls and will be allowed to cool as it passes through the cooling chamber, and means for varying the tension upon different portions of the rolls to anneal certain portions of the strip softer than other portions thereof. 30

6. An annealing furnace including a gas-tight chamber, spaced pairs of rolls in the chamber, the necks of one roll of each pair extending through openings of greater diameter than the necks in the side walls of the chamber, angular flanges surrounding said openings, a collar journaled upon each of said necks and sealed thereon, an angular flange upon each collar having elongated slots therein, a sheet of asbestos or the like between each pair of flanges, bolts located through said first named flanges and through the slots in the second named flanges, springs upon said bolts, and adjustable bearings in which said necks are journaled. 40
